UNITED STATES PATENT OFFICE

BENJAMIN WEINBERGER, OF MOUNT CARMEL, ILLINOIS

PAD SUPPORT FOR PRESSING MACHINES

Application filed May 10, 1929. Serial No. 361,876.

This invention relates to pad supports for pressing machines and an object is to provide a detached enduring pad support for pressing machines constructed and arranged 5 to be placed upon the buck of the pressing machine and including a perforated body of material of approximately uniform thickness and which will not readily warp or deteriorate under the influence of the high 10 degree of heat to which it is subjected on the pressing machine and which is provided with a reticulated cover that will not impede or retard the circulation of steam or air and which support is of an area properly to support the pad.

Another object of the invention is to provide an improved pad support for pressing machines comprising a perforated or cellular body confined within a screen enclosure and 20 designed and adapted to be placed upon the buck of a pressing machine to support the pressing pad.

Other objects will appear from the following description, reference being made to 25 the drawing in which

Fig. 1 is a view partly in section and partly in side elevation showing my improved pad support mounted on the buck of a pressing machine and having the pressing pad mounted thereon.

Fig. 2 is a plan view of the pad support with parts broken away to disclose the several elements, a part of the pressing pad being in position on the support.

Fig. 3 is a sectional view on the line 3—3 of Fig. 2.

Fig. 4 is a detail plan view of one end of the pad support.

In the embodiment of the invention shown 40 my improved pressing pad support comprises a body 1 of compacted and indurated fibrous material or other suitable material or substance of a shape and contour suitable to seat upon and cover the head and buck 2 of a pressing machine for which the device is intended. The body 1 is cellular or perforated, having therethrough numerous holes or perforations 3 distributed approximately evenly throughout said body. These holes 45 or perforations 3 are of sufficient number

and size so that they will not impede the passage or circulation of air or steam from the holes 4 in the top of the head and buck 2 of the pressing machine. The fibrous material of which the body 1 is composed may 55 be asbestos or other suitable fibres.

The upper and lower sides of the body 1 are nearly parallel and sufficiently smooth so that there will be no objectionable recesses, indentations or grooves in either side 60 of said body. It is essential that there be no objectionable recesses, indentations or grooves in the upper side in any event.

In the embodiment shown the body 1 is enclosed by sections 5 and 6 of wire screening having their ends 7 and 8 in lapped arrangement and secured together and to the body 1 by fasteners. For this purpose I have shown fasteners comprising staples 9 passing through both screen sections 5 and 6 and the interposed body 1 and clinched. The series of fasteners 9 as shown extend along the edges of the device crossing split portions at the rounded edges of the screen sections and leaving the intermediate portions of the 75 screen disconnected from the body of the device but resting flatly against said body.

This device constitutes a separate and independent article of manufacture and is designed and adapted to be placed upon the 80 head and buck 2 of a pressing machine so that the separate textile pressing pad 10 may be located upon this support. That is to say, the pressing pad support described has one of the sections of wire screen 5 or 6 on the 85 under side and against the head and buck 2 and the other section of said wire screen on its upper side so as to support the pad 10 out of contact with the body 1. One of these screen sections may be omitted with less beneficial results. Thus, the holes or perforations 3 are kept open because the screens 5 and 6 prevent the cloth of the pressing pad from entering into or stopping said holes. Moreover, the screen on the under side of the 90 device holds the body 1 out of contact with the buck 2 permitting free passage of the hot air or steam from the holes 4 through the screen section 5 or 6, as the case may be, and thence through the holes 3 and the 95 100

screen section 5 or 6 on the upper side of the body 1 and into contact with the pressing pad 10. Thus, the pressing pad is kept in proper condition and is protected from the intense scorching heat of the buck. The wire screening about the body 1 also protects said body and hence performs the double function of protecting said body 1 and of supporting said body so that there is free circulation and passage of steam through said body. This device therefore, by protecting the pressing pad 10, obtains economy in the use of machines of this type, since the duration of usefulness of the pressing pads is greatly extended.

The construction and arrangement may be varied within equivalent limits without departure from the nature and principle of the invention as set forth in the appended 20 claims.

I claim:

1. A device of the character described comprising densely compacted heat resisting non-metallic indurated fibrous material of approximately uniform thickness throughout and having numerous holes therethrough, in combination with a wrapper of screening material enclosing said body.

2. A pad support for pressing machines comprising an indurated non-metallic and non-corrodible body of approximately uniform thickness and density throughout and having a smooth upper surface and numerous holes through said body for the passage of steam from the buck of a pressing machine, in combination with screening laid against the upper and lower sides of said body, and fasteners passing through said screening and said body and securing the screening on the body.

3. A pad support for pressing machines comprising a heat resisting body of indurated fibrous material, said body being of approximately uniform thickness throughout and having a smooth upper surface and numerous holes through said body for passing steam from the buck of a pressing machine, in combination with screening covering the under side of said body and arranged to seat upon the buck of said pressing machine, and means for securing said screening in connection with said body.

4. A pad support for pressing machines comprising a body composed of indurated fibrous material, said body being of approximately uniform thickness throughout and having numerous unobstructed holes therethrough for the passage of steam from the buck of a pressing machine, in combination with screening covering the upper and lower sides of said body, the screening on the lower side of said body being adapted to seat upon and support said body out of contact with the buck of a pressing machine, and the screening on the upper side of said body being

adapted to support a textile pressing pad, and means for securing said screening in connection with said body.

5. A pad support for pressing machines comprising a body composed of indurated fibrous material, said body being of approximately uniform thickness throughout and composed of heat resisting material and having numerous holes therethrough for the passage of steam from the buck of a pressing machine, a section of screening covering the under side of said body and having its edges folded against the edges of said body, a section of screening covering the upper side of said body and having its edges lapping the edges of said first named section of screening, and means passing through said sections of screening and said body and securing said sections of screening and said body in the relationship aforesaid.
